Geo. P. Kimmel.
ATTORNEY.

UNITED STATES PATENT OFFICE.

GIUSEPPE M. PELLETTIERI, OF ST. LOUIS, MISSOURI.

FLY-PAPER HOLDER.

Application filed August 24, 1922. Serial No. 584,058.

To all whom it may concern:

Be it known that I, GIUSEPPE M. PELLETTIERI, a citizen of the United States, residing at St. Louis, in the State of Missouri, 5 have invented new and useful Improvements in Fly-Paper Holders, of which the following is a specification.

This invention relates to a fly paper holder, and has for its object to provide a holder of 10 such class, in a manner as hereinafter set forth, with means for supporting and suspending poisonous fly paper in position to attract the flies, so it can be readily attacked by the flies, and furthermore to provide a 15 holder, with means in a manner as herein-after set forth, whereby the fly paper, while suspended can be moistened.

A further object of the invention is to provide a holder of such class, in a manner as 20 herein-after set forth, with a fly paper support and further with means for detachably securing the paper in position on the support, said securing means permitting of the 25 quick removal of the paper from the support and the substituting of new paper when occasion so requires.

A further object of the invention is to provide a holder of the class referred to, in a manner as herein-after set forth, with means 30 for clamping poisonous fly paper to a support so as to prevent the accidental separation of the paper from the support.

A further object of the invention is to provide a fly paper holder, in a manner as herein-after set forth, having means for suspending and supporting poisonous fly paper, as well as further having means providing a 35 collector for the dead flies.

Further objects of the invention are to 40 provide a fly paper holder which is simple in its construction and arrangement, strong, durable, efficient and convenient in its use, readily assembled and inexpensive to manufacture.

With the foregoing and other objects in view, the invention consists of the novel construction, combination and arrangement of parts as herein-after more specifically described and illustrated in the accompanying 45 drawings, wherein is shown an embodiment of the invention, but it is to be understood that changes, variations and modifications 50

can be resorted to which come within the scope of the claims hereunto appended.

In the drawings wherein like reference 55 characters denote corresponding parts throughout the several views:—

Figure 1 is a vertical sectional view of a fly paper holder in accordance with this invention, 60

Figure 2 is a side elevation, broken away, illustrating the cap member in engaging position with respect to the poisonous fly paper,

Figure 3 is a top plan view of the device. 65

Referring to the drawings in detail, 5 denotes a semi-spherical hollow inner container, which has secured to the upper face of its bottom, as well as projecting upwardly therefrom, a frusto-conical shape hollow support 6, and against the periphery thereof is secured, in a manner as herein-after referred to, a wrapping of poisonous fly paper 7. The paper 7 extends from the top to the bottom 70 of the holder 6.

Secured at its lower end, centrally of the upper face of the bottom of the inner container 5, is the lower end of a vertically disposed hanger rod 8, which is employed for suspending the holder when desired, and the 80 said hanger rod 8, extends upwardly through the support 6, centrally thereof, as well as projecting a considerable distance above the upper end of the support 6. The upper terminus of the rod 8, is provided with an eye 85 9, and which permits of suspending the rod 8 from any suitable support.

Slidably mounted on the upper portion of the rod 8 above the upper end of the support 6, is a frusto-conical shape member 10 having its top formed with an opening 11, for the passage of the rod 8. The lower edge of the body of the cap member 10 is serrated, to provide teeth 12, adapted to engage in the paper 7. The cap 10 is employed for clamping the upper portion of the paper 7 around the upper portion of the support 6, and when in clamping position, the cap member 10 extends down over the top of the support 6, as well as over the upper portion of the paper 100 7, and the teeth 12 are adapted to engage in the paper 7. The cap member 10 frictionally secures the upper portion of the paper 7 around the support 6.

The lower portion of the paper 7 is secured around the base of the support 6, by a tapering sliding collar 13, which when in position, abuts against the upper face of the bottom of the container 5, as shown in Figure 1, and securely clamps the lower portion of the paper 7 to the support 6.

When the sliding collar 13, is mounted in clamping position, it provides, in connection 10 with the body of the container 5, a chamber 14, to which is supplied a body of water 15. The collar 13, is formed with perforations 16, so that the water in the chamber 14, can be supplied to the paper 7, and through the 15 medium of capillary attraction, the paper will be moistened throughout.

The inner container 5, is supported in spaced relation, within an outer container 17, by a series of vertically disposed resilient supports 18, and the said outer container 17 provides a supporting base for the container 5 and also acts as a collector in case the device is shifted and the water split from the inner container 5. The cap 10 and collar 13, can be readily shifted, to permit of the replacing of a new sheet of fly paper 7 when occasion requires, and then furthermore shifted in an opposite direction to provide means for clamping the new sheet 25 of paper to the support 6. As the cap member 10 is conical in contour, and the collar 13 tapered, the clamping of the paper can be had, as is obvious, since the diameter of the cap member 10 with respect 30 to the upper portion of the support 6 and the diameter of the collar 13 with respect to the lower portion of the support 6, is such as to provide for a tight clamping action when the member 10 and collar 13 are in clamping 35 position, under such conditions preventing any accidental displacement of the fly paper, if the holder is shifted accidentally, or swung on its pivot by air currents or 40 otherwise.

45 What I claim is:—

1. A fly paper holder comprising a container, a conoidal-shape support projecting upwardly therefrom and adapted to have a sheet of fly paper detachably connected therewith, a conoidal-shape shiftable cap member cooperating with the upper end of the support to detachably secure the fly paper thereto, and a tapering, shiftable collar cooperating with the lower portion of the support for detachably securing the fly paper thereto.

2. A fly paper holder comprising a container, a conoidal-shape support projecting upwardly therefrom and adapted to have a sheet of fly paper detachably connected therewith, a conoidal-shape shiftable cap member cooperating with the upper end of the support to detachably secure the fly paper thereto, and a tapering, shiftable collar operating with the lower portion of the sup-

port for detachably securing the fly paper thereto, said collar being apertured to permit of the supply of water from the container to moisten the fly paper on the support.

70

3. A fly paper holder comprising a container, a support secured thereto and projecting therefrom and adapted to have the fly paper detachably clamped thereon, a shiftable cap member associating with the upper end of said support and detachably clamping the fly paper thereon, a shiftable ring associated with the lower portion of the support for detachably clamping the fly paper thereon, and a suspension means for 80 said container.

75

4. A fly paper holder comprising a container, a support secured thereto and projecting therefrom and adapted to have the fly paper detachably clamped thereon, a shiftable cap member associating with the upper end of said support and detachably clamping the fly paper thereon, a shiftable ring associated with the lower portion of the support for detachably clamping the fly paper thereon, and a suspension means for 85 said container, said ring being apertured for the passage of water from the container to moisten the fly paper on the support.

90

5. A fly paper holder comprising a container, a conoidal-shape support projecting upwardly therefrom and adapted to have a sheet of fly paper detachably connected therewith, a conoidal-shape shiftable cap member cooperating with the upper end of the support to detachably secure the fly paper thereto, and a tapering, shiftable collar cooperating with the lower portion of the support for detachably securing the fly paper thereto, an outer receptacle surrounding 100 said container, and means carried by the outer receptacle and engaging with the container for connecting it with and supporting it in spaced relation from said receptacle.

95

6. A fly paper holder comprising a container, a conoidal-shaped support projecting upwardly therefrom and adapted to have a sheet of fly paper detachably connected therewith, a conoidal-shape shiftable cap member 115 cooperating with the upper end of the support to detachably secure the fly paper thereto, a tapering, shiftable collar cooperating with the lower portion of the support for detachably securing the fly paper 120 thereto, said collar being apertured to permit of the supply of water from the container to moisten the fly paper on the support, an outer receptacle surrounding said container, and means carried by the outer receptacle and engaging with the container for connecting it with and supporting it in spaced relation from said receptacle.

115

7. A fly paper holder comprising a container, a support secured thereto and pro-

125

130

- jecting therefrom and adapted to have the fly paper detachably clamped thereon, a shiftable cap member associating with the upper end of said support and detachably clamping the fly paper thereon, a shiftable ring associated with the lower portion of the support for detachably clamping the fly paper thereon, a suspension means for said container, said ring being apertured 20 for the passage of water from the container to moisten the fly paper on the support, an outer receptacle surrounding said container, and means carried by the outer receptacle and engaging with the container for connecting it with and supporting it in spaced relation from said receptacle.
- 10 8. A fly paper holder comprising a container, a support secured thereto and projecting therefrom and adapted to have the fly paper detachably clamped thereon, a shiftable cap member associating with the upper end of said support and detachably clamping the fly paper thereon, a shiftable ring associated with the lower portion of the support for detachably clamping the fly paper thereon, a suspension means for said container, said ring being apertured 25 for the passage of water from the container to moisten the fly paper on the support, an outer receptacle surrounding said container, and means carried by the outer receptacle and engaging with the container for connecting it with and supporting it in spaced relation from said receptacle.
- 15 In testimony whereof, I affix my signature hereto.

GIUSEPPE M. PELLETTIERI.
